UNITED STATES PATENT OFFICE.

SIMON A. POLITSKY AND JOSEPH AGUST, OF BOSTON, MASSACHUSETTS, AS
SIGNORS OF ONE-THIRD TO CORNELIUS F. GREENE, OF SAME PLACE.

HYDROCARBON-VAPORIZING BURNER.

SPECIFICATION forming part of Letters Patent No. 657,447, dated September 4, 1900.

Application filed November 16, 1899. Serial No. 737,213. (No model.)

To all whom it may concern:

Be it known that we, SIMON A. POLITSKY and JOSEPH AGUST, of Boston, in the county of Suffolk and State of Massachusetts, have 5 invented certain new and useful Improvements in Hydrocarbon-Vaporizing Burners, of which the following is a description sufficiently full, clear, and exact to enable those skilled in the art to which it appertains or 10 with which it is most nearly connected to make and use the same.

The present invention relates to hydrocarbon-vaporizing burners primarily intended for use as a heating medium; but the invention 15 may also be utilized to advantage in illuminating apparatus.

The type of burner to which the invention particularly appertains is that wherein oil contained in a reservoir of convenient size 20 for portability is put under pressure, so as to be forced to the burner, where it is vaporized and the vapor mixed with air before reaching the place of ignition. In order to start such a burner, it is necessary to employ 25 some means to initiate the vaporization, and it has been customary to provide a cup for alcohol or like fluid, a small charge of which burned below the vaporizing-chamber heats the same and the oil and vapor conduits 30 sufficiently to effect vaporization when communication between the reservoir and burner is set up. The scheme of preheating by alcohol is an objectionable feature of burners of this type because of the danger attending 35 it by reason of the necessity for pumping air into the reservoir after the preheating is under way. The use of the separate and foreign fluid is also objectionable on the score of inconvenience, it being far preferable that 40 no other fluid be required than that with which the device is charged—as, for example, kerosene; but the burning of the latter for preheating purposes in the way the alcohol is burned would be highly objectionable because of the smoke which would result, and, 45 moreover, would not generate a sufficiently-high degree of heat. By the present invention provision is made for dispensing entirely with the use of any foreign fluid, such as alcohol, for preheating purposes and, moreover, provides for burning a charge of fluid ob-

tained from the main supply, and that, too, without smoke and with sufficient heat to quickly accomplish the desired result. Furthermore, in the accomplishment of this result charging of the reservoir with pressure subsequent to preheating is avoided, so that there is no danger to be apprehended on this score in the use of the device. 55

With the above-stated objects in view the invention consists in a number of novel features of construction and combinations of parts, the essential elements of which are recited in the appended claims and a number of forms of embodiment of which are described hereinafter and illustrated in the accompanying drawings. 60

Of said drawings, Figure 1 represents in central vertical section an apparatus embodying features of the invention. Figs. 2 and 3 are sections taken on lines 2 2 and 3 3 of Fig. 1. Fig. 4 represents a portion of the apparatus in section, as in Fig. 1, but on an enlarged scale. 70

The reference-letter *a* designates an oil-reservoir of well-known general form and equipped with an air-pump *b* and a filling-cap *c* and having a stand-pipe *d* rising from its top at the center to conduct oil to the burner located at the top of the stand-pipe. 75 A valve-casing, in the form of a union-coupling *e*, is incorporated in the stand-pipe and a suitable valve *e'* arranged therein to control the flow of oil through the stand-pipe. The burner at the top of the latter is of a well-known 80 general form, comprising an annular vaporizing-chamber *f*, into the bottom of which, at diametrically-opposite points, branches *d'* of the stand-pipe enter, and out of the bottom of which at other diametrically-opposite 85 points lead vapor-pipes *f'*, which unite between the branch pipes *d'* in a valve-casing *f''*. A nozzle *f'''* screws into the upper end of the valve-casing, the opening in said nozzle flaring downwardly to form a valve-seat. 90 The lower portion of the valve-casing is bored and screw-threaded for the engagement therewith of a stem *f⁴* of a needle-valve *f⁵*, the stem having a knob *f⁶* by which to turn it, and thereby adjust the valve to regulate the 95 flow of vapor through the nozzle. A crown *g* fits over the vaporizing-chamber, with an 100

intervening space g' to constitute a mixing-chamber, wherein the vapor and air commingle before issuing through the perforations g^2 of the crown, where ignition takes place. The crown is preferably surmounted by a cap g^3 , having an outstanding flange g^4 to spread the flame, the usual flaring cup g^5 being employed.

At a point above the valve-union e the stand-pipe is surrounded by a preheating-burner, whereby the parts above may be heated so as to vaporize the oil when communication is opened between the reservoir and the burner proper, said preheating-burner being of the following description: An annular wick-holder h is supported around the stand-pipe and receives an annular wick h' , preferably of asbestos, and a pipe h^2 extends between said wick-holder and the oil-reservoir, there being incorporated in it a valve-casing h^3 , having a valve h^4 to control the flow of oil to the wick. In order to provide for the burning of the oil thus supplied to the wick with a blue flame and to prevent smoke, a combustion-chamber of the following description is arranged to extend above the wick to a point just below the branch d' of the stand-pipe. A perforated cylindrical shell i fits around the outside of the upstanding portion of the wick-holder, resting against an outstanding base portion thereof, and through the perforations of said shell air in limited quantity reaches the wick. A grooved ring or collar j rests upon the bottom of the wick-holder within the upstanding portion of the same and around the stand-pipe, and a cylindrical shell j' seats within the groove of the ring, said shell being vertically corrugated, so as to form passages j^2 adjacent to the wick and up which vapors from the oil in the wick may pass under the influence of the currents of air induced through the perforations of the shell i . The upper part of said corrugated shell is embraced by a perforated shell k , having a flaring lower end portion k' just above the wick and calculated to induce the passage of vapor up the channels j^2 , wherein such vapor commingles with air, finally issuing through the perforations of the shell k , whereat it burns in blue-flame jets. A sleeve m fits snugly around the stand-pipe and has at the top an outstanding flange m' , extending over the top edges of the shells j and k and somewhat beyond the latter, the said flange being formed with perforations at which vapor may burn.

In operation, the valves e' and h^4 being closed, the pump is worked to create air-pressure within the reservoir, and thereafter the valve h^4 is opened to admit oil to the preheating-burner in sufficient quantity to charge the wick thereof, the said valve being thereupon closed and a match applied to the wick. By reason of the arrangement of a combustion-chamber of the character described the oil thus fed to the preheater will burn with a blue flame within the chamber, and the parts

above will quickly be brought to a high degree of heat amply sufficient for vaporizing purposes, while no smoke rises from the pre-heater. The burner proper having thus been heated, together with the oil-conduits leading to it, the valve e' will be opened, and the oil rising through the stand-pipe will be vaporized as it progresses, and only vapor will pass from the chamber f through the pipes f' . Such vapor in passing across from the nozzle f^3 to the mixing-chamber g' takes with it sufficient air for purposes of perfect combustion at the perforations of the crown g .

It will now be seen that the constructions described are well calculated to thoroughly fulfil the objects primarily stated. However, it is to be understood that the invention is capable of embodiment otherwise than as here shown.

Having thus explained the nature of the invention and described a way of constructing and using the same, though without attempting to set forth all the forms in which it may be made or all of the modes of its use, it is declared that what is claimed is—

1. A hydrocarbon-burner of the character described, comprising a base constituting an oil-reservoir and being equipped with pressure-supplying means; an oil-conveying stand-pipe rising from said reservoir and having a valve to control the flow of oil; a preheating-burner of annular form surrounding the stand-pipe above the valve thereof and consisting of an oil-holder and a combustion-chamber thereabove with restricted air-inlets; an oil-pipe communicating at its upper end with the oil-holder of the preheating-burner and at its lower end with the reservoir; a valve controlling the flow of oil through said pipe; and a main burner surmounting the stand-pipe and communicating therewith through branches which overhang the combustion-chamber of the preheating-burner.

2. A hydrocarbon-burner comprising an annular oil-holder having an oil-supply conduit communicating therewith, a perforated cylindrical shell rising from the said holder at the outer part thereof and constituting the outer wall of a combustion-chamber, an inner wall of such chamber rising from the oil-holder at the inner part thereof, and a perforated shell encompassing said inner wall at its upper part, vertical vapor passage-ways being formed between said encompassing shell and the inner wall of the combustion-chamber.

3. In a hydrocarbon-burner, the combination of an oil-reservoir, an annular wick-holder, a conduit connecting the reservoir with the wick-holder, a wick in the latter, a perforated cylindrical shell rising from the wick-holder on the outer side of the wick and forming the outer wall of a combustion-chamber, an inner wall of such chamber rising from the wick-holder on the inner side of the wick, and a perforated shell encompassing the upper portion of said inner wall, vertical passage-ways being formed between the lat-

ter and the encompassing perforated shell, substantially as and for the purpose described.

4. A hydrocarbon-burner comprising an annular oil-holder having an oil-supply conduit communicating therewith, a perforated cylindrical shell rising from the said holder at the outer part thereof and constituting the outer wall of a combustion-chamber, an inner wall of such chamber rising from the oil-holder at the inner part thereof, and a perforated shell encompassing said inner wall at its upper part, and having a flaring lower end portion, vertical vapor passage-ways being formed between said encompassing shell and the inner wall of the combustion-chamber.

5. In a hydrocarbon-burner the combination of an oil-reservoir, an annular wick-holder, a conduit connecting the reservoir with the wick-holder, a wick in the latter, a perforated cylindrical shell rising from the wick-holder on the outer side of the wick and forming the outer wall of a combustion-chamber, an inner wall of such chamber rising from the wick-holder on the inner side of the wick, and a perforated shell encompassing the upper portion of said inner wall and having a flaring lower end portion, vertical passage-ways being formed between the inner wall and the encompassing perforated shell, substantially as and for the purpose described.

6. A hydrocarbon-burner comprising an annular oil-holder having an oil-supply conduit communicating therewith, a perforated cylindrical shell rising from the said holder at the outer part thereof and constituting the outer wall of a combustion-chamber, an inner wall of such chamber rising from the oil-holder at the inner part thereof, and a perforated shell encompassing said inner wall at its upper part, vertical vapor passage-ways being formed between said encompassing shell and the inner wall of the combustion-chamber; together with a sleeve within the latter and having a perforated flange extending over the top edge of the same and of the perforated encompassing shell.

7. A hydrocarbon-burner comprising an annular oil-holder having an oil-supply conduit

communicating therewith, a perforated cylindrical shell rising from the said holder at the outer part thereof and constituting the outer wall of a combustion-chamber, an inner wall of such chamber rising from the oil-holder at the inner part thereof, and vertically corrugated, and a perforated shell encompassing said inner wall at its upper part, vapor-passages being formed by the corrugations of the latter and the said encompassing shell. 60

8. In a hydrocarbon-burner, the combination of an oil-reservoir, a conduit rising therefrom, a main burner at the top of said conduit, a preheating-burner surrounding the latter and comprising an annular wick-holder and 65 wick, a perforated shell rising from the wick-holder on the outer side of the wick, a corrugated shell rising from said holder on the inner side of the wick, a perforated shell surrounding the upper portion of the corrugated 70 shell, and a sleeve fitting around the conduit inside the corrugated shell and having a perforated flange extending over the top edge of the latter and the top edge of the perforated shell which surrounds it; together with a 75 valved conduit connecting the oil-reservoir with the wick-holder.

9. In a hydrocarbon-burner, the combination of an oil-reservoir, an annular wick-holder, a conduit connecting the same with the reservoir, a wick in the holder, and an annular combustion-chamber rising from the wick-holder and comprising an outer perforated shell, an inner imperforate shell corrugated to provide vertical vapor-passages, a 80 85 perforated shell surrounding the upper portion of the corrugated shell, and a perforated disk extending over the upper ends of the latter and the said surrounding shell, substantially as described. 90

In testimony whereof we have signed our names to this specification, in the presence of two subscribing witnesses, this 8th day of November, A. D. 1899.
